CIRCUIT BREAKER

Raymond N. Rowe, Plainville, Conn., assignor to
The Trumbull Electric Manufacturing Com-
pany, Plainville, Conn., a corporation of Con-
necticut

Application May 16, 1936, Serial No. 80,030

4 Claims. (Cl. 200—149)

My invention relates to circuit breakers. In arc interruption, particularly for circuit breakers, a principle of arc extinction known as compression interruption has been used. The present invention is an improvement in devices in this field of arc interruption.

One object of this invention is to simplify the structure used in arc interrupters of the compression type.

10 Another object is to strengthen the compression chambers in these breakers.

Still another object is to improve the action of compression chamber seals in these arc interrupters.

A further object is to make a chamber seal that is comparatively inexpensive when compared to the seals now known to me.

These objects, and others, are accomplished by making a circuit breaker in which the contacts 20 are separated within a closed chamber. As is usual in breakers of the compression arc interruption type, the separated contacts draw an arc which heats the gases enclosed in the compression chamber. The heating of these gases causes 25 them to expand, until the increased gas pressure in the chamber produces an increase in the arc drop sufficient to extinguish the arc.

Because this whole action depends upon a close sealing of the chamber, it is important that the 30 wall of the chamber through which any movable contact is projected be provided with a strong and efficient packing or the like, to prevent escape of the gases under pressure. Leather, or other flexible, semi-resilient material, has been 35 used for this packing. According to the present invention I make the seal for the movable contact member out of metal or other strong and substantially inflexible and non-resilient material. However, the mere close fitting of this seal 40 around the moving member is insufficient effectively to prevent escape of the heated gases. To overcome this defect, the wall of the sealing member, or the wall of the movable contact carrier, or both, is provided with a series of coarse 45 circumferential corrugations or serrations which, as explained below, prevent escape of enough gas under pressure to affect the circuit-breaking operation.

In the accompanying drawings I have illus- 50 trated several forms that my improved seal may take, and have shown one form of switch and circuit breaker which may be used in connection therewith.

In these drawings—

55 Fig. 1 is a plan view of a two-pole ganged

switch and circuit breaker utilizing my invention. The parts are in "on" position.

Fig. 2 is a vertical section along line 2—2 of Fig. 1.

Fig. 3 is a side elevation of some of the switch 5 parts.

Fig. 4 is a sectional view of the switch and circuit breaker parts in "off" position.

Fig. 5 is a similar view of these parts in "tripped" position.

Fig. 6 is an enlarged sectional view of a compression chamber and contact carrier illustrating the preferred form of my invention.

Fig. 7 is an enlarged section of a modified form of seal for the contact carrier.

Fig. 8 shows another form of seal according to my invention.

Fig. 9 shows still another form of seal for the contact carrier.

In order to illustrate a completely operative 20 device I have shown a novel form of switch and circuit breaker in which my improved chamber seal is used. It should be understood that many other suitable types of switch and breaker mechanism could be used without departing from the 25 spirit of the present invention.

In the device shown, the switch has an insu- 30 lating base 10 which may be connected to other bases of identical switches by means of screws or rivets 11 which pass through connecting straps 30 12 and 13. As shown, two of these switches are ganged together. It is obvious that they may be used singly or in combinations greater than two when desired.

Mounted on the base is a frame piece 14, 35 U-shaped in cross section, each arm of the U carrying an extended leg 15. Straddling the frame is a switch yoke 16, pivoted as at 17 in a recess of the base. The yokes of a plurality of ganged switches are connected together by an 40 insulating connecting bar 18, operated by a han- 45 dle 19.

The switch throw piece 20 is pivoted on axis 21 between the arms of the frame and has a cross bar 22 which connects the sides of the piece 45 together. At its lower end, the throw piece carries a rod 23, which extends on either side outside of the confines of the switch frame 14. Between each end of this rod 23 and ears 24 on yoke 16 are stretched springs 25. The rod 23 50 passes through the contact-carrying plunger 26 which has a contact 27 at one end. The position of the yoke pivot 17 is so arranged with respect to the pivot axis 21 of the throw piece and the ends of the springs 25 that movement of the 55

yoke produces a snap action of the plunger and contact in each direction.

A trip piece 28 is also pivoted on axis 24 in the switch frame. This trip piece has a catch roller 29 rotatably mounted between its sides. A resetting bar 30 connects the sides of the piece together.

Arms 31, on the trip piece 28, carry a cross-rod of catch 32 which extends outward far enough to engage one edge of the switch throw piece 20 to prevent clockwise rotation of the throw piece beyond the catch. The free ends of the arms 31 are engaged by a cross-head 33 on a bar 34. This bar is slidably mounted in a pressure plate 35 which in turn is pivotally held at its ends by seats in the ends of legs 15 of the switch frame. A spring 36 surrounds bar 34 and presses against head 33 and plate 35. These parts are so positioned with respect to the pivot axis of trip piece 28 that the spring 36 always exerts a pressure tending to turn trip piece 28 in a counter-clockwise direction.

A catch piece 37 is pivotally mounted in frame 14 as at 38 by ears or pivot lugs 39. One end of this catch piece normally abuts against roller 29 on trip piece 28, thus preventing spring 36 from pushing the trip piece to releasing position. See Figs. 2 and 4. To insure normal engagement with the roller 29, a small, light spring 40 is secured between the opposite end of the catch piece and a fixed part of the switch base or frame. An adjusting or calibrating screw 41 is threadedly engaged with the outer end of catch piece 37 and is held in its adjusted positions by lock-spring 42. This catch piece is actuated upon a short circuit or overload by any suitable electro-responsive device. As shown, the electro-responsive device consists of a bimetallic strip 43, fixedly mounted at one end with respect to the switch base by conducting support 44.

The free end of the bimetallic strip is attached to one end of a flexible current-carrying cable 45, the other end of the cable being secured to one end of the contact plunger 26. This free end of the thermostatic element will flex upwardly when the strip is heated, thus engaging the end of adjusting screw 41 and tripping the catch piece 37 by overcoming the slight pressure of counterbalancing spring 40. To prevent unnecessary current flow through the switch parts, a strip of mica or other flexible insulating material 46 is secured to the top surface of the thermostatic strip 43 between the end of screw 41 and strip 43.

Current is supplied to the electro-responsive element through support 44. Terminal 47 makes connection with a strap 48 which in turn is electrically connected to support 44 by means of a screw or the like 49.

When a plurality of switches are ganged together, adjacent catch pieces 37 are connected for simultaneous movement by means of an insulating bar 50, held to the catch pieces as by screws 51.

The opposite current side of the switch preferably contains the compression chamber. This chamber is composed of a cup-shaped piece 52 which has a stationary contact piece 53 in its bottom. The cup and contact are electrically connected to terminal 54 by means of a strip 55. The edges of cup 52 are crimped around a heavy insulating tube 56, which fits the inside of the cup very closely.

Seated and sealed within the insulating tube 56 is a hard metallic hollow sealing member 57.

The walls of this sealing member fit closely around the surface of the movable contact carrier 26 but not tightly enough to bind the parts together. As shown in Fig. 6, the walls of the sealing member are provided with a serrated surface in the form of a coarse screw thread surrounding the movable contact carrier. This is the preferred form of sealing means by which the compression within the chamber is maintained sufficiently high to aid in arc extinction.

The operation of the switch is as follows, assuming the parts to be in the "off" position of Fig. 4: the switch handle 19 and yokes 16 are moved to the left, the springs 25 being put under increasing tension. When the springs have stretched their maximum amount they start to contract, pulling the rod 23 to the left. This rod swings the switch throw piece 26 clockwise and pushes the contact-carrying plunger rod 26 against stationary contact 53. The trip piece 28 and catch piece 37 do not move. The parts are then in the "on" position of Figs. 1, 2 and 3.

Movement of the handle in the opposite direction causes the above mentioned parts to function in a reverse manner, throwing the switch into normal off position. Stops or lugs 58 on the switch frame limit the extent of movement of the switch yokes.

When the switch is in "on" position, current flows from terminal to terminal through the following parts: terminal 47, strap 48, screw connection 49, support 44, bimetallic strip 43, cable 45, plunger 26, contact 27, contact 53, compression chamber wall 52, connecting strip 55, and terminal 54.

On a short circuit or overload the thermostatic strip 43 will be heated and flex upwardly. This will trip the switch mechanism to separate the contacts. Action is as follows: when strip 43 flexes upwardly it lifts screw 41 upward, tilting catch piece 37 counter-clockwise around its pivots 39. The other end of the catch piece will then become disengaged from catch roller 29 and spring 36 is able to push trip piece 28 in its counter-clockwise direction. As soon as cross rod 45 or catch 32 engages the edge of the switch throw piece 20, both throw piece and trip piece will be pushed counter-clockwise together, and rod 23 with plunger 26 will be pulled away from contacting position. Springs 25 will also move to pull yoke pieces 16 part way toward off position.

The yoke and handle are prevented from going to full "off" position by means of the trip resetting piece 59 which is fixed to the yoke piece 16. The under surface of this resetting piece will engage resetting bar 30 of trip piece 28 and the pressure of spring 36 will prevent springs 25 from pulling the yoke any farther. The parts are now in the "tripped" position of Fig. 5.

To reset the switch, after the bimetallic strip 60 has cooled down and assumed normal position, it is merely necessary for the operator to force the handle to full "off" position.

When the handle is so forced, resetting piece 59 bears against resetting bar 30 and pushes trip piece 28 (against the action of spring 36) clockwise into the position of Fig. 4. Counterbalance spring 40 will pull one end of catch piece 37 downwardly and the other end will engage catch roller 29 to hold the trip piece in place. Resetting bar 30 will also engage the upper surface of catch piece 37 to insure proper resetting at the end of the switch handle movement. The parts are now all in the position of Fig. 4 because the switch throw piece 20 and plunger 26 were al-

ready in "off" position and have been held there by tension of the spring 25.

When the contacts 27 and 53 are separated under load or short circuit, arcing will take place within the compression chamber. Because the chamber is sealed, the pressure, built up by the expanding gases heated by the arc, will act to extinguish the arc. To seal the moving contact carrier at its place of entry into the chamber I have provided the structure described above in connection with Fig. 6. Other forms are illustrated in Figs. 7, 8 and 9.

It is theorized that the expanding gases, because of the serrations in the wall, are alternately expanded and contracted. It is believed that this alternate expansion and contraction in rapid succession creates an obstruction to the escape of the gases and that this is why the proper compression is maintained in the chamber.

In Figs. 6 and 7 the serrations are in the form of coarse screw threads, in the first case on the inside of the aperture of the chamber wall, and in the second case on the outer walls of the contact carrier. These two forms are preferred mainly because of the extreme ease of their manufacture.

In Figs. 8 and 9 are illustrated other forms of serrations, namely, a series of adjacent circumferential grooves. In Fig. 8 these grooves are within the aperture of the chamber wall, and in Fig. 9 they are around the outer surface of the contact carrier. The spiral arrangement of the grooves in these forms does not seem to affect the efficiency of the seal produced, probably because the arc pressure is explosive in nature and tends to act equally in all directions.

It should be understood that the contact carrier of Fig. 6 may be used with the sealing tube 40 of either Fig. 6 or Fig. 8. The contact carriers of Figs. 7 and 9, however, may be used with the sealing tubes of Fig. 6, Fig. 7, or Fig. 8.

Note that although I have shown a switch with a contact carrier that reciprocates through one 45 wall of the compression chamber, other forms of switches utilize contact carriers which have a twisting or rotary movement through one wall of a chamber. My improved sealing means is equally effective in this other mounting of the 50 contact carrier and the appended claims should be read with this in mind.

Because of the use of metal instead of other material in my seal, the structure is extremely strong and durable.

The tendency of ordinary seals to cause sticking between the chamber wall and the moving contact carrier is obviated by my improved structure.

Another advantage is the fact that although 60 the present seal effectively holds the pressure within the chamber during arc explosion, there is sufficient communication with the outer air to enable the pressures inside and outside of the chamber to equalize by slow leakage after arc 65 interruption. This aids in cooling the chamber and shortens the periods during which the walls of the chamber are subjected to internal pressure.

A further advantage of my invention is the 70 simplicity of the compression chamber structure. The parts of this chamber are easily manufactured and assembled, and produce a rugged, inexpensive device.

In the following claims, I have used the words "substantially circumferential serrations" for want of better generic terminology to cover both

the screw thread grooves and the non-communicating circumferential grooves. This meaning should be kept in mind in interpreting the scope of the invention.

The switch mechanism per se is claimed in my application Serial Number 100,414, filed September 12, 1936.

I claim:

1. In a circuit breaker, circuit making and breaking means including a cup-shaped member 10 having a contact in the bottom thereof, a metal bushing having an aperture in line with said contact, insulating means interposed between the bushing and the edge of the cup-shaped member and extending inside the wall of the cup-shaped 15 member from the bushing part way toward the bottom of the cup-shaped member, said cup-shaped member, insulating means and bushing together constituting a closed chamber in which an arc may be formed, said chamber being of 20 such size that the heat of the arc is sufficient to raise gas pressure within said chamber to an amount capable of assisting in choking the arc, a contact making plunger slidable in said aperture and having its inner end adapted to make 25 and break contact with the contact in the bottom of the cup-shaped member, the plunger and the bushing having between them grooves constituting substantially the only passage for the relief of gas pressure within said chamber, the fit be- 30 tween said sliding plunger and said bushing being such as to effectively hold gas pressure within the chamber during existence of the arc but yet capable of allowing a leakage of gas to substantially equalize the pressure inside and outside of 35 said chamber after interruption of said arc.

2. A circuit breaker having relatively fixed and movable contacts between which an arc may form on opening the circuit, a compression chamber in which said arc is formed, said chamber being of 40 such size that the heat of the arc is sufficient to raise the pressure of gas within the chamber to an amount capable of assisting in choking the arc formed, a movable contact carrier passing through a wall of said compression chamber, and 45 gas sealing means around said movable contact carrier where it passes through said chamber wall, said sealing means including a close fit between said wall and carrier and a plurality of circumferential serrations on either the movable 50 contact carrier or on the chamber wall around it and through which it passes, the fit between said movable carrier and chamber wall being such as to effectively hold the gas pressure within said chamber during existence of said arc but yet 55 capable of allowing leakage of gas to substantially equalize the pressure inside and outside of said chamber after interruption of said arc.

3. In a circuit breaker having a fixed and a movable contact between which an arc may form 60 on separation of the contacts, a compression chamber around said contacts and in which said arc is formed, said chamber being of a size such that the heat of the arc may raise the pressure of gas within the chamber to an amount capable of assisting in choking the arc formed, a carrier for the movable contact passing through a wall of said chamber, the improvement which includes 65 a gas sealing means around the contact carrier where it passes through said chamber wall, said sealing means including a plurality of closely adjacent circumferential serrations of generally V-shape on either the movable carrier or wall of the chamber around the carrier, the carrier and the 70 75

contiguous portion of the chamber wall being of metal and their fit being such as to effectively hold gas pressure within said chamber during existence of said arc but capable of allowing leakage of gas to substantially equalize the pressure inside and outside of said chamber after interruption of said arc.

4. A circuit breaker having relatively fixed and movable contacts between which an arc may form
10 on opening the circuit, a compression chamber in which said arc is formed, said chamber being of such size that the heat of the arc is sufficient to raise the pressure of gas within the chamber to an amount capable of assisting in choking the arc formed, a movable contact carrier passing

through a wall of said compression chamber, and gas sealing means around said movable contact carrier where it passes through said chamber wall, said sealing means including a close fit between said wall and carrier and a screw thread on either the contact carrier or the chamber wall contiguous thereto, the fit between the movable carrier and the contiguous portion of the chamber wall being sufficient to hold the gas pressure within the chamber during existence of said arc 10 but also capable of allowing leakage of gas from the chamber to substantially equalize the pressure inside and outside of said chamber after interruption of said arc.

RAYMOND N. ROWE. 15
